ANGELES, CALIFORNIA, A CORPORATION OF CALIFORNIA

GAS-OPERATED SCREW-TYPE HEAD FOR PUNCTURING CLOSURES

Application filed January 30, 1929. Serial No. 336,157.

Our invention relates to a device for releasing fluid from a container, and in its preferred embodiment is in the form of a device for releasing fire extinguishing fluid from a container. In our co-pending applications 5 entitled Pressure operated means for puncturing closure diaphragm, Serial No. 208,795, filed July 27, 1927, and Device for puncturing closure disc, Serial No. 208,717, filed July 27, 10 1927, we have illustrated various devices for accomplishing this result.

It is one of the objects of the present invention to provide a device, which has a puncturing member, which is operated by a fluid 15 rotated rotor.

It is another object of our invention to provide a device having a puncturing member, which is advanced into penetrating position by a rotation thereof.

20 A still further object of the invention is to provide a device of the character mentioned, in which the rotor, which operates the puncturing member, may be actuated by the pressure or velocity.

25 It is also an object of the invention to provide a device of this character in which the puncturing member is designed, so that it will not obstruct the flow of fluid.

Other objects and advantages of the invention 30 will be pointed out in the following description.

Referring to the drawings, in which our invention is illustrated:

Figure 1 is a vertical section through one 35 form of our invention, which is operated by a fluid pressure;

Figure 2 is a plan section taken on the line 2-2 of Fig. 1;

Figure 3 is a plan section taken on the line 40 3-3 of Fig. 1;

Figure 4 is a vertical section through another form of the invention, which is operated by the velocity of the fluid; and

Figure 5 is a plan section taken on the line 45 5-5 of Fig. 4.

Referring to the form of the invention illustrated in Figs. 1 to 3 inclusive, the numeral 11 designates a container having an outlet opening 12, which opening 12 is formed through a threaded projection 13. Adapted

to close the opening 12 is a closure member in the form of a disk 14, which is secured in place by an annular nut 15. The invention provides a body 17, which is secured to the projection 13 by means of a union nut 18, which is 55 screwed on to the threaded projection 13. The body 17 provides a fluid chamber 20, which, when the closure member 14 is punctured, communicates with the opening 12.

Extending into the chamber 20 is a puncturing member 21. This puncturing member 21 has a lower knife edge 22, adapted for penetrating the closure member 14 when the puncturing member is operated. Formed in the puncturing member 21 is a longitudinal 60 cavity 24, which communicates with the lower end thereof, and which is in communication with the chamber 20 by means of lateral openings 25. When the closure member 14 is punctured, the fluid escaping through the opening 12 may pass through the cavity 24 and the openings 25 into the fluid chamber 20. The fluid may pass from the chamber 20 through a pipe 26 connected therewith.

The upper end of the puncturing member 20 is provided with screw threads 27, which cooperate with screw threads 28, provided in an opening 29, into which the upper end of the puncturing member extends. When the puncturing member is rotated in a clockwise 70 direction, the co-action of the screw threads 27 and 28 cause it to advance downward and to penetrate the closure member 14.

The upper part of the body 17 provides a cylindrical rotor chamber 31 the upper side 85 of which is closed by a cover plate 32, this cover plate 32 being secured to the top of the body 17 by means of machine screws 33. Extending through the rotor chamber 31 on the axis of the puncturing member 21 is a 90 rotor shaft 34. The lower end of the rotor shaft 34 is provided with a non-cylindrical opening 35, into which the upper end 36 of the puncturing member 21 extends. The puncturing member may move axially with 95 respect to the rotor shaft 34, but cannot rotate relative thereto. This lower end of the rotor shaft journals in an opening 36^a of the body 17 and the upper cylindrical part 37 thereof journals in an opening 38 of the 100

cover 32. That portion of the rotor shaft 34, which extends through the rotor chamber 31, is non-cylindrical in cross-section, as indicated at 39. Adapted to operate in the rotor chamber 31 is a rotor or impeller vane 41, having a hub 42, which surrounds the portion 39 of the rotor shaft 34. Formed in one portion of the rotor chamber 31 is a radially extending wall 43, having a stop 44 formed at the inner end thereof, against which the rotor 41 may abut when it is in the unactuated position shown in full lines in Fig. 2, this being the normal position of the rotor. Connecting to the rotor chamber 31 adjacent to the web 43 and in a tangential relation to the rotor chamber is an entrance passage 46, by means of which a fluid under pressure is delivered to the rotor chamber 31. The means for supplying this pressure may be in the form of a pipe 47 for conveying a fluid under pressure to the entrance 46, or it may be in the form of some device for creating a pressure, such for example as an explosion plug, which is shown in our application entitled Device for puncturing closure disc, mentioned in the first part of the specification.

The web 43 is provided with a vent opening 49, which permits any gas or fluid in the rotor chamber to escape when the rotor 41 is caused to rotate by the fluid under pressure introduced through the entrance opening 46.

As shown in Fig. 1, the upper end of the rotor shaft 34 extends above the cover plate and is provided with a crank 50, having a manually engageable handle 51, by means of which the device may be manually operated.

The operation of this form of our invention is substantially as follows:

When it is desired to release the fluid from the container 11, it is necessary to rotate the puncturing member 21, so that it may be advanced downward a sufficient distance to penetrate the closure disk 14. This may be accomplished either by a manual operation of the device or by a fluid operation of the device. For a fluid operation of the device, a fluid pressure is delivered through the entrance passage 46 to the rotor chamber 31. The fluid under pressure causes the rotor 41 to rotate in the rotor chamber 31 in the direction indicated by the arrow 53 of Fig. 2, the rotor 41 being moved into the position indicated by dotted lines 54 of Fig. 2. When the rotor moves into the dotted line position, any fluid or gas, which is in front of it is forced from the rotor chamber through the vent opening 49.

The rotor shaft 34 is revolved substantially one revolution when the rotor is operated as explained, and due to the connection between the rotor shaft and the puncturing member 21, the puncturing member is likewise rotated substantially one revolution.

The screw threads 27 and 28 cause the puncturing member to move downward, so that the closure disk 14 is penetrated. This will permit fluid to pass through the opening 12 of the container 11, the cavity 24, the openings 25, the fluid chamber 20 and into the pipe 26.

If the device is to be manually operated, the handle 51 of the crank 50 is engaged and the rotor shaft 34 is rotated the same distance as it is rotated by means of the rotor 41.

The second form of our invention, which is illustrated in Figs. 4 and 5, includes a body 60, which is secured to the projection 13 of the container 11 by means of the union member 18. This body 60 has a small chamber 61 adapted to receive the nut 15, which is screwed on to the projection 13 for holding the closure disk 14 in place. This form of the invention provides a puncturing member 62, which extends through an opening 63 of the body 60 into the chamber 61. The puncturing member is provided with threads 64, which cooperate with threads 65 formed in the opening 63 in order to advance the puncturing member when it is rotated. The lower end of the puncturing member is provided with a knife edge 66, which is in a position to puncture the disc 14 when the puncturing member 62 is advanced downward.

The puncturing member is provided with a longitudinal cavity 67, the lower end of which communicates with the opening 12 of the container when the closure disc is penetrated. The upper end of the cavity 67 is connected by lateral openings 68 with a fluid chamber 69, provided by the body 60. Connecting to the fluid chamber 69 is a pipe 70, by means of which the fluid is delivered to a point of utilization.

The upper part of the body 60 and a cover 72, which is bolted to the body 60 by bolts 73, cooperate to provide a rotor chamber 74. Adapted to operate in the rotor chamber 74 is a rotor 75, which is adapted to be operated by the velocity of a fluid. The rotor 75 is in axial alignment with the puncturing member 62. This rotor 75 has vanes 76, which extend from a hub 77. As shown in Fig. 4, the lower end of the hub 77 is centralized by a bearing ring 78, supported in the upper part of the fluid chamber 69. The upper end of the hub 77 has an extension forming a stub shaft 80 journaled in an opening 81 of the cover 72. The extreme upper end of the stub shaft has a crank 82 connected to it, whereby the hub may be manually rotated. As shown in Figs. 4 and 5, the lower end of the hub 77 is provided with a polygonal socket 84, into which a correspondingly shaped projection 85 of the puncturing member 62 extends. The puncturing member 62 may move axially with respect to the rotor 75, but cannot rotate relative thereto.

The upper part of the rotor chamber 74 has an entrance opening 87 connected to it, by means of which the fluid is supplied thereto. The fluid may be delivered to the entrance opening 87 by means of a pipe 88 having a check valve 89.

The operation of this form of the invention is as follows:

The fluid is introduced to the rotor chamber 74 through the entrance opening 87. The fluid passes downward through the rotor chamber 74 into the fluid chamber 69 and outward through the pipe 70. In passing through the rotor chamber 74 the velocity of the fluid causes the rotor 75 to rotate. This rotation is transferred to the puncturing member 62, which, by reason of the screw threads 64 and 65 causes the puncturing member 62 to advance downward and to penetrate the closure disk 14. When the closure disk 14 is penetrated, the fluid in the container will pass through the opening 12 thereof, cavity 67, the openings 68 and into the fluid chamber 69. This fluid released from the container 11 will pass from the fluid chamber 69 with the first mentioned fluid, which operates the rotor 75. When the fluid pressure in the chamber 69, caused by the release of fluid from the container 11 exceeds that in the pipe 85, the check valve 89 will close and prevent a back flow of fluid through the pipe 88.

The device may be manually operated by means of the crank 82, which causes the rotor 75 to rotate and causes the puncturing member 62 to be advanced downward and penetrate the closure disk 14, as previously described.

From the foregoing description, it will be apparent that the invention will be quick and positive in operation. The important feature rests in the combination of a puncturing member, which is advanced by rotation, and a fluid operated rotor for causing the puncturing member to be rotated, so that it will be advanced in order to penetrate the closure disk 14.

We claim as our invention:

1. In a device for use in connection with a container having a closure for closing the opening thereof, the combination of: a puncturing member, means whereby said puncturing member is adapted to be advanced by rotation to puncture said closure; and a fluid-operated rotor for causing operation of said means.

2. In a device for use in connection with a container having a closure for closing the opening thereof, the combination of: a puncturing member operable by rotation to puncture said closure; a rotor operatively connected to said puncturing member; and means for directing a fluid to operate said rotor.

3. In a device for use in connection with a

container having a closure for closing the opening thereof, the combination of: a body; a puncturing member having threaded engagement with said body, said puncturing member adapted to advance and puncture said closure when said puncturing member is rotated; and fluid-operated means for rotating said puncturing member.

4. In a device for use in connection with a container having a closure for closing the opening thereof, the combination of: a body; a puncturing member having threaded engagement with said body, said puncturing member adapted to advance and puncture said closure upon being rotated; a rotor operatively connected with said puncturing member, said puncturing member being movable relative to said rotor to engage said closure; and means for directing a fluid to operate said rotor.

5. In a device for use in connection with a container having a closure for closing the opening thereof, the combination of: a body forming a fluid chamber; a puncturing member having threaded engagement with said body and extending in said fluid chamber, said puncturing member adapted to advance and puncture said closure when said puncturing member is rotated, said puncturing member having a cavity adapted to connect with said opening of said container when said closure is punctured, said cavity conveying fluid to said fluid chamber; and fluid-operated means for rotating said puncturing member.

6. In a device for use in connection with a container having a closure for closing the opening thereof, the combination of: a body forming a fluid chamber; a puncturing member threadedly supported by said body and extending in said fluid chamber, said puncturing member adapted to advance and puncture said closure when said puncturing member is rotated, said puncturing member having a cavity adapted to connect with said opening of said container when said closure is punctured, said cavity conveying fluid to said fluid chamber; a rotor connected to said puncturing member, said puncturing member being movable relative to said rotor; and means for directing a fluid to operate said rotor.

7. In a device for use in connection with a container having a closure for closing the outlet thereof, the combination of, a body, a member operable to open the closure, a fluid actuated rotor, and means whereby said member is operated by operation of the rotor.

8. In a device for use in connection with a container having a closure for closing the outlet thereof, the combination of, a body, a member operable to open the closure, a fluid actuated rotor operable in a chamber in the body, and means whereby said member is operated by operation of the rotor, said means

including a threaded engagement between the body and said member.

9. In a device for use in connection with a container having a closure for closing the outlet thereof, the combination of, a body, a member operable to open the closure, a fluid actuated rotor operable in a chamber in the body, and means whereby said member is operated by operation of the rotor, said means including a threaded engagement between the body and said member, and a connection between the rotor and said member whereby said member is rotated by the rotor.

10. In testimony whereof, we have hereunto set our hands at Los Angeles, California, this 24th day of January, 1929.

SCOTT E. ALLEN.
OZRO N. WISWELL.
